SHORT FILLER BUNCH MACHINE

Hjalmar E. Carlson, Brooklyn, N. Y., assignor to
International Cigar Machinery Company, a
corporation of New Jersey

Application November 26, 1937, Serial No. 176,594

7 Claims. (Cl. 131—21)

This invention relates to scrap bunch cigar machines, more particularly to an improved tobacco feed for the same. Heretofore, rotary tobacco feeds have been provided with drums wherein the tobacco has simply tumbled over and over before removal of a charge, with the result that small scrap accumulated in the bottom of the drum and the larger pieces were fed out first. The main object of the same is to avoid this disadvantage of prior rotary feeds. In the particular embodiment selected to illustrate the invention, the tobacco is placed into a hopper leading the same into a slowly and continuously rotating cylindrical drum provided with internal axially extending vanes which serve to pick up the tobacco at the bottom of drum and carry it upwardly and dump it downwardly on to an intermittently driven conveyor belt extending into the drum. In the present construction, therefore, the small scrap will be picked up with the large scrap without any tendency for the latter to accumulate in the bottom, wherefore small, large or mixed small and large scrap will be handled equally well and the small and large scraps will be evenly mixed. The belt moves intermittently for advancing a quantity of tobacco loosely deposited thereon, slightly in excess of the amount required for one cigar bunch, under a leveling mechanism and into a chute directing the same to the measuring chamber of the machine. After a charge has been leveled and delivered to the chamber a cam operated door or gate of the measuring chamber is closed and the column of loose tobacco therein is pushed by a horizontally slideable spring-tensioned plunger into a charge-measuring pocket of the general type disclosed in the Reissue Patent 20,334, granted to Gladeck, et al., dated April 20, 1937, wherein it is thereby compressed to the proper density determined by the adjustment of the plunger spring. A further object is to stop the movement of the feed-in belt and drum when there is an oversupply of tobacco in the chamber, and for this purpose the driving mechanism thereof is controlled by the compacting plunger of the measuring chamber.

The means for closing the measuring chamber gate also swings a chute about its pivot and deposits the tobacco in a uniform layer in the chamber. The chute is so constructed that its wide upper walls converge into a narrow point at the exit end and thus force the elongated scraps into a position extending across the width of the chute with all the long scraps having their greatest dimensions extending in the same direction, which constitutes another objective of the invention.

Incorporated approximately midway in the chute

is a shutter which is urged into closed position by a coil spring when the chute is swung inwardly, said shutter covering the discharge opening while the measuring chamber gate is closed, thus catching any tobacco falling from the feed-in conveyor belt and arresting the same until the gate is again opened. Still another object, therefore, is to prevent dribbling of tobacco on to the closed door of the measuring chamber.

The principal advantage of this machine is that it handles small, large or mixed small and large scrap equally well and keeps the small and large scrap evenly mixed, and in loose state, thus producing cigar bunches of uniform and springy consistency; that is, it eliminates all possibility of having a run of bunches consisting mostly of long scrap interspersed with runs of bunches having mostly short scrap. With these and other objects not specifically mentioned in view, the invention consists in certain constructions and combinations hereinafter described and claimed.

In the accompanying drawings which form a part of this specification and in which like characters of reference indicate the same or like parts:

Fig. 1 is a partial side view of the short filler bunch machine selected to illustrate the invention; and

Fig. 2 is a front view of the same.

Referring to the drawings, the side frames 10 of the machine support a table 11 provided with a pair of pedestals 12 and 13 to which are fastened the stationary end walls 14 and 15, respectively, of the revolving cylindrical drum 16. A hopper 17 into which the tobacco may be dumped is attached to the rear wall 15 and communicates with a suitable opening in said wall whereby the tobacco is deposited in the interior of the drum.

Each set of pedestals 12 and 13 support a stationary shaft 18 on which are loosely mounted rollers 19 engaging the circular channel bands 20 encircling the drum 16 and thereby supporting the same. A sprocket 21 secured on a shaft 22 supported in side frames 10 and suitably driven in a manner which need not be shown, drives a chain

23 running over a sprocket 24 loosely mounted on a shaft 25 carried by a bracket 26 fastened on table 11. A ratchet wheel 27 fastened to sprocket 24 is provided with a pawl 28 held in engagement with ratchet 27 by a leaf spring 29 and imparting motion to an arm 30 fastened on shaft 25. Shaft 25 carries a bevel gear 31 meshing with a bevel gear 32 fixed on a shaft 33. Over a sprocket 34 mounted on the latter runs a chain 35 driving a sprocket 36 which is integral with a sprocket 37 loosely mounted on shaft 18. The latter sprocket

drives an endless chain 38 fitting tautly in the channel band 39 and imparts motion to the drum 16. Shaft 33 at one end is journaled in bracket 26, and its other end is mounted in a bracket 40 which also supports shaft 18.

A sprocket 41 fixed on a shaft 42 supported in the side frames of the machine is intermittently driven as will be hereinafter described, and transmits intermittent motion to a shaft 43 by a chain 44 running over a sprocket 45 fixed on said shaft. Shaft 43 is supported by brackets 46 and 47 attached to the front wall 14 of the drum. To these brackets are fastened bars 48 and 49 which extend axially into the drum 16 and support the rear shaft 50 of the conveyor belt 51. A plate 52 connecting the bars 48 and 49 serves as a supporting member for the upper loop of the conveyor belt. Belt 51 is driven by a pulley 53 fixed on shaft 43 and runs over an idler pulley 54 mounted on shaft 50.

The continuously rotating drum 16 is provided with a plurality of spaced vanes or scoops 55 projecting inwardly from the inner periphery of said drum and serving to pick up the tobacco scrap T and dump the same on to the intermittently driven conveyor belt 51. The belt 51, when in motion, transports the tobacco deposited thereon under a series of revolving rakes or fingers 56 which level or trim the tobacco to predetermined thickness and return the surplus tobacco back into the drum. Thus, a uniform layer of loose tobacco emerges through a rectangular opening 57 in the wall 14 and is delivered to a chute leading to the measuring chamber of the machine which will be presently described. Vertical plates 58 and 59 extending along the upper run of the belt 51 and supported by brackets 46 and 47 respectively, form a discharge chamber therealong for the tobacco. The inner ends of the plates 58 and 59 extend inwardly through the opening 57 and terminate in tail-like portions 60 which permit the excess tobacco to flow over these tails when it is pushed back by the fingers 56. The bars 48 and 49 may carry strips 61 and 62, respectively, which rest on the upper loop of the belt 51 to prevent the tobacco from falling off the belt and also may be extended around the pulley 53 to prevent tobacco particles from getting between the belt and pulley 53 at the discharge end of the conveyor.

The fingers 56 are mounted on a shaft 63 disposed above the plates 58 and 59 and carried by arms 64 and 65 adjustably mounted on a stationary shaft 66 and fastened thereon by a set screw 55 or the like (not shown) whereby said fingers may be raised and lowered with respect to the conveyor belt 51 to permit a stream of the desired thickness of scrap tobacco to be delivered. Shaft 63 is provided with a sprocket 67 driven from a sprocket 68 by a chain 69, sprocket 68 being fastened to a sprocket 70 loosely mounted on shaft 66 and sprocket 70 being driven by a chain 71 running over a sprocket 72 fixed on the intermittently driven shaft 43.

When the belt 51 advances it causes the tobacco to fall from its exit end into a funnel 75, which is attached to the outer ends 76 of the bars 48 and 49 leading it into a chute 77 which directs the tobacco scrap to the measuring chamber 78. The front wall of the chute 77 slopes inwardly toward the rear wall, and the latter terminates in a curved extension 79 which initially engages the opened gate of the measuring chamber or may be appropriately secured thereon to leave a narrow gap at its lower end, so that the elongated scraps of to-

bacco entering the apex between these members are forced to assume a position extending transversely of the chute and also while dropping down through said gap into the measuring chamber 78 in the event such a gap is present. The chute is swingably mounted at its upper end on a cross rod 80 supported by projecting lugs 81 of brackets 46 and 47. A strap 82 secured to a projecting flange 83 of chute 77, supports one end of a link 84 connected to a link 85 fastened on a rock-shaft 86. An arm 87 on shaft 86 is pivotally connected to an eye 88 of a rod 89 which is suitably actuated by a cam (not shown), to swing said chute from under the funnel 75. The turning of rock-shaft 86 also opens and closes the measuring chamber gate 90 which is mounted thereon and fits snugly between the adjustable upright side walls 91 of the inlet of the chamber. The curved portion 79 of the chute, which also fits snugly between the walls 91, then approaches the gate 90 to engage the same or leave a narrow gap, and retreats after the tobacco is deposited thereon, thereby depositing the latter uniformly in the measuring chamber. Chute 77 also supports a spout 154 fastened to the inner face of the rear wall of the chute and carrying a rock shaft 155 equipped with a shutter plate 156. Rock-shaft 155 is provided with a coil spring 160 which normally maintains the plate 156 in a horizontal position. The shaft 155 also carries at one end a trip arm 157 which engages a stop screw 158 carried by a strap 159 secured to one of the walls 91 whereby the shutter is turned upwardly and opened as the chute approaches the opened gate of the measuring chamber. When the chute 77 is swung inwardly back to initial position, the coil spring 160 closes the shutter, thereby arresting any tobacco which may dribble from the feed belt 51 and prevent it from falling on to the measuring gate 90, after the same has been closed. When the chute again returns to its previous position ready to receive tobacco, the shutter is opened by screw 158 and permits any tobacco which may have accumulated on the shutter to fall into the measuring chamber.

The tobacco T delivered by the belt 51 into the measuring chamber 78 is pushed into a charge transfer (not shown) and compacted therein to the desired density, is of the general type disclosed in the above mentioned patent. The charge transfer forms a continuation of the measuring chamber, and the tobacco is pushed into it by a plunger 92 attached to a rod 93 slidably mounted in a lug 94 of slide 95 mounted on a rail 96. A spring 97 on the rod 93 is seated against the rear end of plunger 92 and may be adjusted to the desired tension by a bearing against spring 97 and thumb-screw 98 threaded into the lug 94 and a plate 99 guided at its lower end in a slotted portion of slide 95, the adjustment of the tension of spring 97 thus regulating the density of the tobacco compressed by the plunger 92. Slide 95 is connected by a link 100 (Fig. 2) to a cam lever 101 which by suitable means is actuated from a cam (not shown) to move the plunger to and fro.

The extent of movement of the feed belt 51 in each cycle is so adjusted, by means to be presently described, that a surplus of tobacco is delivered to the measuring chamber. Thus, after the column of tobacco in the chamber 78 has been compressed and a bunch charge severed from the column there is still a quantity of compressed tobacco left in the measuring chamber. In the next cycle, as the belt advances, another charge of tobacco is delivered to the measuring chamber. Thus the

excess tobacco will continue to accumulate in the measuring chamber and from time to time will prevent plunger 92 from reaching the end of its predetermined stroke. At such times an adjustable screw 102 attached to the lug 94 will fail to engage a trip lever 103 placed in its path and thus preventing the feed belt 51 from moving during the next cycle of the machine and discontinuing delivery of tobacco until the measuring chamber is cleared of excess tobacco.

The trip lever 103 is pivoted on a stud 104 in bracket 105 and fastened to a rocker arm 106. A torsion spring 107 anchored in the head of the stud is attached to the trip 103 and normally maintains it in the path of the screw 102. The arm 106 is connected to a link 108 pinned to one end of an arm 109 attached to a pivot shaft 110 supported on lugs 111 of table 11. On the other end of shaft 110 is fastened an arm 112 pivotally connected to one end of a link 113 pinned to a latch 114 fulcrumed on a stud 115 in one side frame 10. The latch 114 is provided with a shoulder 116 (Fig. 1) adapted to engage the upper end of a lever 117 pivotally mounted on a stud 118 supported in the side frame of the machine. Lever 117 is equipped with a cam piece 119 which is normally maintained by the latch in the position shown with its high portion 120 in position to engage roller 121 and stop the drive of a sprocket 122, as will now be described, shortly before the measuring chamber gate is closed during compaction of the tobacco. Roller 121 is carried by a finger 123 mounted on a pintle 124 secured in arm 125 loosely mounted on drive shaft 22. Finger 123 has a notch 126 adapted to engage a dog 127 secured in the rotating disk 128 fixed on shaft 22 and normally held in engagement therewith to thereby turn arm 125 and the sprocket 122 fastened to said arm.

When sprocket 122 turns it drives a chain 130 running over a sprocket 131 loose on a stationary shaft 132 supported in the side frames 10. An arm 133 loosely mounted on shaft 132 is provided with a stud 134 on the outer end of which is pivotally mounted a finger 135 provided with a cam roller 136 adapted successively to engage the raised lobe 137 formed by relatively adjustable stationary cams 138 and 139, thus disengaging the pawl 140, which is fastened to finger 135, from the ratchet wheel 141 loose on shaft 132. Pawl 140 is secured to the inner end of stud 134, which passes through sprocket 131, and is normally held in engagement with ratchet wheel 141 by a spring 142 and thereby imparts motion to its attached sprocket 143 and drives a chain 144 running over a sprocket 145 fixed on shaft 42. The sprocket 41 on the latter drives the chain 44, thereby imparting motion to the feed belt 51 and fingers 56.

The cam 138 is fixed on shaft 132 and has fastened thereto the adjustable cam 139 provided with elongated slots 146 through which the bolts 147 pass. Thus resetting of the cam 139 with respect to cam 138, is permitted and when the relation of the cams is correctly set, they may be locked together by bolts 147. It will be seen that if cam 139 is moved in a clockwise direction, the pawl will remain in engagement with the ratchet for a greater period of time and drive belt 51 longer than when the cam 138 is adjusted in a counter-clockwise direction. In this manner the belt 51 can be adjusted to advance a greater or lesser distance, thereby delivering more or less tobacco to the measuring chamber to suit the

conditions necessary to produce a well formed bunch.

When the lever 103 is tripped by screw 102 the latch 114 is disengaged from lever 117 and permits a spring 150 to pull said lever against a stop pin 151 carried by latch 114 and thereby move the high portion 120 of cam piece 119 out of the path of roller 121, permitting the driving members 123, 127 to remain engaged and feed additional tobacco to the measuring chamber during the next cycle of the machine. As the screw 102 retreats, the spring 107 tends to return the lever 103 to its previous position, permitting a spring 152 to reset the latch against lever 117 as a roller 153 carried by the driving disk 128 engages the inner face of cam 119 and restores it to its initial position. Roller 153 is suitably arranged to engage and reset cam 119 during each revolution of disk 128, in the event it has been tripped.

Since the drum 16 rotates very slowly, provision is made for manually turning said drum rapidly to cause the scoops 55 to shower tobacco on to the feed belt 51 at the start of a new run. This is accomplished by providing shaft 25 (Fig. 2) with a pin 161 adapted to engage a notch 162 of a crank handle 163 shown in dotted lines. Upon turning handle 163 in a clockwise direction shaft 18 is driven through bevel gears 31, 32 and chain drive 35, thereby imparting motion to the chain 38 and turning drum 16.

It may be noted that the belt is disposed to one side of the center of the drum, wherefore tumbling of the tobacco supply against the belt is prevented. If the belt were centrally arranged and the level of tobacco were high enough, the vanes 55 might tumble the tobacco against the belt and break up long scraps. Moreover the measuring chamber and bunch rolling mechanism will be located nearer the molding or concentrator turret, so that the attendant may transfer the rolled bunches to the turret more conveniently.

What is claimed is:

1. The combination with a measuring chamber, of spaced members arranged to guide tobacco into said chamber, and means for dumping quantities of scrap tobacco between said members for delivery to said chamber, said members providing a gap of such a width that the longer scraps will be turned, in passing therethrough, into a position extending transversely of the measuring chamber.

2. The combination with a measuring chamber provided with a door movable from a closed position into an upright position to admit tobacco to said chamber, of a pivoted chute adapted to swing into position adjacent the upright door to deliver tobacco to the measuring chamber and then away from the door to permit closure thereof, a device for actuating said door, means for delivering a quantity of tobacco to said chute while it is in position adjacent the upright door, a shutter pivotally mounted on said chute and normally closed to prevent dribbling of tobacco, and a stop arranged to engage said shutter and open the same when the chute is swung into position adjacent the upright gate.

3. The combination with a measuring chamber provided with a door adapted to move outwardly to admit tobacco to the chamber, of a device for actuating said door, a pivoted chute arranged to deliver tobacco to said chamber and provided with an extension arranged to approach the opened door to provide a gap of such a width that long scraps will be turned in passing therethrough, into position extending transversely of the measuring chamber, and mechanism for swinging said

chute to cause its extension to approach and retreat from the opened door.

4. The combination with a measuring chamber, of a rotary drum adapted to receive a supply of scrap tobacco and provided with internal vanes adapted to pick up tobacco and carry it upwardly therein, an endless traveling belt arranged within said drum to receive tobacco from said vanes and adapted to feed tobacco to said chamber, means for compacting the tobacco in said chamber, mechanism intermittently driving said belt and controlled by said means for interrupting the movement of said belt whenever there is an over-supply of tobacco in said chamber, said mechanism being adjustable to regulate the extent of advancing movement of said belt.

5. The combination with a rotary drum adapted to receive a supply of scrap tobacco and provided with internal members adapted to carry tobacco upwardly therein, an endless traveling belt arranged within said drum to receive quantities of tobacco from said members, rotary rakes for leveling to a predetermined thickness the tobacco so deposited on said belt and pushing the surplus tobacco backward on the belt, mechanism for intermittently driving said belt, and means for revolving the drum about said belt at such a speed that a surplus of tobacco is deposited on the belt in each cycle.

6. The combination with a rotary drum having an end wall adapted to admit a supply of tobacco and provided with internal members adapted to carry tobacco upwardly therein, an endless traveling belt arranged within said drum to receive quantities of tobacco from said members, a slotted wall having an opening through which said belt passes, rotary rakes for leveling to a predetermined thickness the tobacco so received on said belt, and said rakes moving inward through said slots to return surplus tobacco to the interior of said drum, and strips extending inwardly along said belt from said rakes and provided with tapered inner ends over which surplus tobacco may flow and drop down into the drum.

7. The combination with a rotary drum having a horizontal axis and adapted to receive a supply of scrap tobacco in its bottom and provided with internal vanes extending generally in the direction of rotation of the drum to provide pockets wherein tobacco is lodged at the bottom of said supply, an endless traveling belt having a horizontal upper run entering the interior of said drum at a position above said supply and underlying the side of drum whereon said vanes have a downward movement, whereby the tobacco may drop from said pockets on to said run.

HJALMAR E. CARLSON.
